RUBBISH OR GARBAGE RECEPTACLE

Filed Sept. 3, 1930

Inventor
-Julius Tellinger-
By Horatio E. Bellows
Attorney

UNITED STATES PATENT OFFICE

JULIUS TILLINGER, OF PROVIDENCE, RHODE ISLAND

RUBBISH OR GARBAGE RECEPTACLE

Application filed September 3, 1930. Serial No. 479,459.

My invention relates to receptacles for the accommodation of offal or refuse.

The essential objects of my invention are the adaptability in a single structure of the facile tilting and facile complete removal of the container member relatively to its framework; to enable the utilization of a part of the framework as a closure means for the container while the parts are in normal association; to afford in such a structure means for a facile display; to produce a receptacle, characterized by such advantages, capable of construction from relatively light weight material at small expense without sacrifice of strength.

To the above ends essentially my invention consists in such parts and in such combinations of parts as fall within the scope of the appended claims.

In the accompanying drawings which form a part of this specification,

Figures 1 and 2 are a front and a side elevation respectively of my novel device, and

Figures 3 and 4, sections respectively taken on lines 3-3 of Figure 2, and 4-4 of Figure 1.

Like reference characters indicate like parts throughout the views.

The framework of my receptacle includes two vertically disposed skeleton side frames 8 of relatively thin metal and of identical outline, and is, therefore, capable of quantity manufacture and speedy assemblage. In detail each upright comprises a substantially horizontal base 9, terminal uprights 11, merging into inwardly and upwardly directed arms 12 terminating in a substantially rectangular web 13 provided centrally of its upper edge with a downwardly directed slot 15, open at its upper end and constituting a bearing. Integral with the rear upper corner of the web is a rearwardly and upwardly inclined arm 18 terminating in a laterally enlarged upright, enlarged portion or head 19. An upright bracing strip or web 20 is integral with an intermediate portion of the rearmost arm 12 and of the arm 18. The horizontal base 9 is provided with an intermediate upwardly directed rectangular loop portion 21 forming,

in combination with the uprights 11, depending legs 22. In this instance rollers 23 are mounted on pivot pins 24 in the lower portion of the legs 22.

A plurality of horizontally disposed spacing or cross rolls or braces 25, in this instance four in number, arranged in couples, one above the other, connect the lower portions of the two frames 8. Each of the four cross rods have reduced threaded end portions 27 extending through perforations 28 in the uprights 11 and upon these portions are nuts 29 engaging the outer faces of the frames. A similar cross rod 31 has reduced threaded ends 32 extending through perforations 33 in the opposite heads 19, and carry nuts 35 upon their ends engaging the outer faces of the heads.

Pivoted and detachably mounted in the above described framework is a transversely rectangular container 40 comprising downwardly tapering front and rear walls 41 and 42, similarly tapering side walls 44, and a bottom or floor 46, all composed of thin sheet metal. The container is open at its top, and the upper ends of edges 47 of the side walls 44 are arched or arcuate and project above the upper ends of the other walls.

Fixed by bolts 48 and nuts 49 or otherwise to intermediate portions of the container side walls 44 are plates 50 from each of which project trunnions comprising necks 52 and heads 53, the latter being provided with diametrical holes 55 through which loosely pass ring handles 56. The trunnion necks 52 rest loosely in the open bearings 57 where they are retained by gravity, and are readily inserted or removed at will by grasping and upwardly lifting upon the rings 56.

An arched cover 58 normally resting upon the top edges 47 of the side walls 44 of the container closes the open upper end of the latter. This cover is of sheet metal and has the material of its rear margin inwardly, forwardly, and upwardly bent to form an integral internal sleeve 60 which loosely surrounds the rod 31 upon which the cover is journaled. A stop rod 61 of the construction identical with that of rod 31 has its reduced threaded ends engaged in threaded perfora-

- tions 62 in the head portions 19 of the frame behind the journal rod 31 and in the path of the rearward travel of the cover. Nuts 63 engage the projecting ends of the rod 61.
- 5 Fixed by screws 64 or by fusing to the forward portion of the top of the cover is a hand hold 65. Rearwardly directed pins 66 are in this instance located in the upper ends of the container wall 42.
- 10 Upon the front and back of the container walls 41 and 42 respectively are racks 69 and 70. Each rack comprises vertically disposed channelled interspaced guide strips 72 provided with closed lower ends 74 wherein are slidably mounted a display card or plate 75.
- 15 In using my device, access to the container 40 may be gained by lifting the cover 56 and swinging it rearwardly to rest upon the stop rod 61 as shown in broken lines in Figure 3.
- 20 The container 40 may be then swung upon its trunnions to any desired convenient angle for introducing or removing its contents or for cleansing purposes, as shown in broken lines in said figure. When desired, as already suggested, the entire container may be lifted out of engagement with the framework and be removed at a distance to be emptied.
- 25 It will be observed that the cover 58, which is arched and all four of whose edges extend beyond the vertical planes of the upright walls of the container, protects the contents of the latter from rain and inclement weather. Further, that the mounting of the cover 58 for the container upon the stationary framework of the receptacle not only serves as a cover for both the receptacle and the framework, but adds to the speed and convenience of removing and returning the container to original position.
- 30 It will be further noted that the described construction of the skeleton side frames including their adaptability for quantity production combined with the sheet metal construction of the cover and container unites economy with strength.
- 35 I claim:—
1. In a receptacle of the character described, two interspaced flat skeleton side frames, a substantially rectangular sheet metal container open at its top and including sides provided with arched upper edges, trunnions upon intermediate portions of the sides pivotally supported in intermediate portions of the side frames, said frames being provided with perforations below the container, spacing rods provided with reduced ends and with threads upon the ends passing through the perforations, nuts engaging the threads, said frames being provided also with perforations in their upper ends in the rear of the container, a cross rod provided with reduced threaded end portions extending through the last mentioned perforations, a rectangular arched cover resting upon the top of the container and completely cover-

ing the open top thereof; a sleeve integral with the cover loosely surrounding the cross rod, and a stop member in the frame in the rear of the cross rod in the path of the cover.

2. In a receptacle of the character described, two interspaced flat skeleton side frames, each frame comprising a substantially horizontal base, uprights integral with the ends of the base, inwardly and upwardly directed arms integral with the upper ends of the uprights, a substantially rectangular web integral with the upper ends of the arms provided in its upper edge with a downwardly directed slot open at its upper end, a rearwardly and upwardly inclined arm provided with an enlarged upper end, and a brace integral with intermediate portions of the last mentioned arm and one of the first mentioned arms, a transversely rectangular container comprising vertical front and rear walls, side walls, and a floor, plates fixed to intermediate portions of the side walls, trunnions on the plates resting loosely in the slots, spacing rods connecting the uprights, a cross rod mounted in the upper ends of the rearwardly directed arm behind the container, a stop member in the last mentioned ends adjacent the cross rod, and a cover carried by the cross rod resting by gravity upon the top of the container.

3. In a receptacle of the character described, two interspaced flat skeleton side frames, a container provided with an open top pivotally mounted in the side frames, spacing rods connecting the frames below the container, a cross rod connecting the upper ends of the frames, a cover pivotally attached to the cross rod and normally enclosing the open end of the container, a stop member in the frames in the rear of the cross rod in the path of the cover, and a display rack including parallel interspaced guide strips provided with channels and fixed to the front of the container.

In testimony whereof I have affixed my signature.

JULIUS TILLINGER.
